M. D. NEILSON

UNDERGARMENT OF THE BLOOMER TYPE

Filed July 15, 1922

14 INVENTOR:
MARY D. NEILSON.
BY Whiteley and Ruckman
ATTORNEYS.

UNITED STATES PATENT OFFICE.

MARY D. NEILSON, OF MINNEAPOLIS, MINNESOTA.

UNDERGARMENT OF THE BLOOMER TYPE.

Application filed July 15, 1922. Serial No. 575,332.

To all whom it may concern:

Be it known that I, MARY D. NEILSON, a citizen of the United States, residing at Minneapolis, in the county of Hennepin and State of Minnesota, have invented certain new and useful Improvements in Undergarments of the Bloomer Type, of which the following is a specification.

My invention relates to undergarments of the bloomer type and has for its object to provide an undergarment or bloomer adapted to be slipped up over the hips and secured around the waist, preferably by an elastic band, and which is so constructed as to give increased fullness at the crotch, particularly directly back from the median line at the center of the front in conjunction with a short and straight front to the garment. The garment embodying my invention may be conveniently fabricated of three pieces only, to-wit, a back member and a pair of specially shaped front members adapted to be sewed to the edges of the back member and to be sewed together and to a bottom portion of the back member to provide legs and provide the requisite fullness; or the garment may be cut in a single piece which embodies the back member and the two front members, the front members being provided with portions for union together and for union with a portion of the back member to provide a garment having legs and a short front and crotch fullness extending directly back at substantially right angles from the median line of the front.

The full objects and advantages of my invention will appear in connection with the detailed description thereof and the novel features of the invention are particularly pointed out in the claims.

In the drawings, which illustrate the application of my invention in one form,—

Fig. 1 shows the garment in use upon a wearer in an extreme sitting position. Fig. 2 shows the garment in use upon a wearer in an extreme standing position. Figs. 3, 4 and 5 are pattern views of the unassembled members of the garment when the

same is made up of three pieces. Fig. 6 is 50 a pattern view of the members of Figs. 3, 4 and 5 in relative position but not united. Fig. 7 is a pattern view of the construction of Fig. 6 showing how the garment may be cut from a single piece and obtain substantially the advantages as where it is made from three pieces.

As illustrated, the back member 10 is provided with side edges 11, 12, preferably cut straight with a top edge 13 slightly curved, 55 with a concave bottom edge 14 and with two straight edges 15, 16 extending angularly between the respective side edges 11, 12 and bottom edge 14, the side edges being angularly disposed so that the top portion is of less width than the bottom portion. The front pieces 17, 18 are symmetrically formed as shown of substantially rectangular shape with side edges 19, 20, bottom edges 21, 22, top edges 23, 24 and inner side edges 25, 26. 60 From about the center of the edges 25 and 26 the material is cut back substantially at right angles to said edges as indicated at 27, 28, leaving inwardly-cut edge portions 29, 30. In fabricating the garment the edge 11 is sewed to the edge 19, being gathered to produce a side seam of the length of edge 19, and thereby producing fullness at the back: The edge 12 is similarly sewed to edge 20, and edges 27, 29 of piece 17 are sewed to 65 edges 28, 30 of piece 18, the uniting point of edges 29 and 30, producing a central front seam as indicated at 31 in Fig. 1. The edges 25, 26 are then sewed to the curved bottom edge 14 of the member 11, 70 the leg openings being formed by the circumferential extent of the material comprised in the extent of the bottom edges 15, 21 and 16, 22 of the respective side and back pieces 17, 10 and 18, 10. The similar member made by the union of edges 25 and 26 with edge 14 is shown at 32 in Figs. 1 and 2, while the union formed between portions 27, 28 extending rectangularly from edges 25, 26 is shown at 33 in Fig. 1. 75 The effect of the union of edges 29, 30 is, as stated, to make a straight short seam directly down the median line of the front

of the garment, which continues into the union of offset portions 27, 28 backward at the crotch in the seam 33 at substantially a right angle to the seam 31, throwing the material backward so as to produce a great increase of fullness in the garment at the back and in the crotch where it is needed, leaving the front of the garment with a short straight line from the waist and with 10 no excess of material or bagging effect.

In the construction of Fig. 7 the fulling together of side seams 11, 19 and 12, 20 is eliminated, the side or front portions being formed integral with the back portion and 15 eliminating that union, as is clearly shown in dotted lines in Fig. 7, but the edges 25, 27, 29 and 26, 28, 30, and bottom edge 14, are identically the same in the single piece member as in that fabricated from three 20 pieces and are united in the same manner, giving the straight front seam 31, the transversely-extended back seam 32 and the backwardly-turned seam 33 in exactly the same way as is done where the three 25 pieces are employed. Owing to the fact that the use of the three pieces permits side fulling, the garment may be fitted somewhat more accurately and give greater fullness at the back by using three pieces, but in the 30 provision of extra material at the crotch extending directly back from the median line of the front of the garment, the one-piece construction produces exactly the same results as the three-piece construction.

35 I claim:

1. A bloomer garment comprising back and front portions, the back portion having a centrally-disposed curved bottom edge, the front portions being provided with symmetrically-disposed edges each formed with upper and lower portions extending in parallel relation but being offset by increased width of material in the lower parts and being connected by an edge portion extending 40 substantially at right angles to the first named edge portions, the upper and connecting edge portions being united to one another, and the lower edge portions being united to the curved edge of the back portion, whereby legs are formed with crotch fullness extending directly back from the center line of the front of the garment.

2. A bloomer garment comprising back and front portions united together so as to 45 provide a bottom edge with two symmetrical portions extending angularly to the median line thereof, and a central edge portion between the angularly-disposed bottom edge portions, the front portions of the garment 50 being provided with symmetrically-disposed edges each formed with upper and lower portions extending substantially at right angles to the symmetrical portions of the bottom edge, but being offset by increased 55 width of material in the lower parts of the

front portions, said edges being connected by an edge portion extending substantially at right angles to the first-named edge portions, the upper and connecting edge portions being united to one another, and the lower edge portions being united to the central bottom edge portion, whereby legs are formed with crotch fullness extending directly back from the center line of the front of the garment. 70

3. A bloomer garment comprising a back member which in its unassembled condition is formed with upwardly converging side edges and a composite bottom edge consisting of two portions each angularly extended from one of said side edges in symmetrical 80 relation to the whole back member and of a continuous central portion extending between the symmetrically disposed portions and making at its ends the same angles with each of said symmetrically disposed portions, a 85 pair of front members having side and bottom edges and united with the side edges of the back member so that said bottom edges form a continuation of the symmetrical parts of the bottom edges of the back member, said 90 front members having other side edges substantially parallel with the first-named side edges and comprising offset parallel portions connected by portions extending substantially at right angles thereto, the upper and 95 connecting edge portions being united to one another, and the lower edge portions being united to the centrally-disposed edge of the back member, whereby legs are formed with 100 crotch fullness extending directly back from the center line of the front of the garment.

4. A bloomer garment comprising a back with a pair of symmetrical extensions at the sides thereof, and having a continuous centrally positioned bottom edge portion, the extent of material along the top to bottom center line of said back being substantially as great as the greatest top to bottom extent of material of said extensions, each of said 105 extensions having increased width of material along their sides at the lower parts thereof with a side edge length corresponding to one-half the length of said bottom edge, to which the respective side edges of said increased width of material are sewed 110 to form the legs of the garment, the remainder of the side edges of the extensions being sewed together along the median line of the front of the garment.

5. A bloomer garment comprising a back member having a continuous centrally positioned bottom edge portion, a pair of symmetrically front members each secured to a side of the back member in similar relation to said bottom edge, the extent of material along the top to bottom center line of said back member being at least as great as the greatest extent of material of said front members at their point of union with the back member, each of said front members 115 120 125 130 135 140 145 150

having increased width of material along its side at the lower part thereof with side edge length corresponding to one-half of the length of said bottom edge, to which the respective side edges of said increased width of material are sewed to form the legs of the garment, the remainder of the side edges of the front members being sewed together along the median line of the front of the garment. In testimony whereof I hereunto affix my signature.

10 MARY D. NEILSON.
